UNITED STATES PATENT OFFICE.

STANLEY WASZKIEWICZ, OF PASSAIC, NEW JERSEY.

DRIER.

1,345,523.

Specification of Letters Patent.

Patented July 6, 1920.

Application filed August 15, 1919. Serial No. 317,661.

To all whom it may concern:

Be it known that I, STANLEY WASZKIEWICZ, a citizen of Poland, residing at 123 Ninth street, Passaic, county of Passaic, and 5 State of New Jersey, have invented certain new and useful Improvements in Driers, of which the following is a specification.

This invention has for its object the provision of means whereby a laundried article 10 may be subjected to the air, in the process of drying, in a novel and convenient manner.

A further object is to provide a wash hanger capable of being attached to the 15 walls of a building, adjacent to the window, so that the laundried articles may be conveniently placed on the wash line and extended outwardly from the window without danger to the operator.

20 These and other like objects, which will become more fully apparent as the description progresses, are attained by the novel construction and combination of parts hereinafter described, and shown in the accompanying drawings, forming a material part 25 of this disclosure, and in which—

Figure 1 is a top plan view showing a wash hanger made in accordance with the invention and indicating its application.

30 Fig. 2 is a partial side elevational and vertical sectional view of same, the section being taken on line 2—2 of Fig. 1.

Fig. 3 is an enlarged view of the rotary hanger head.

35 Fig. 4 is a transverse sectional view taken on line 4—4 of Fig. 3.

Fig. 5 is a side elevational view, partially in section, the section being taken on line 5—5 of Fig. 1.

40 Fig. 6 is a top plan view showing a modification in construction, and

Fig. 7 is a side elevational view of the same, the parts being shown in another position.

45 Referring to the drawings in detail, the numeral 10 indicates conventionally the wall of a building containing a window frame 11, in which operate sashes 12 and 13, respectively upper and lower.

50 Rigidly engaged to the wall 10, centrally of and below the window frame 11, is a bracket 14 having an extending hollow angular arm 15 adapted to rigidly support a tapering bar 16, provided with a flattened horizontal hollow head 17, and passing 55 through the head 17 is a rectangular bar 18

removably engaged and held in position by a collar 19 clamped by a screw 20.

Formed at the upper end of the bar 18 is a conical head 21, mounting an eye 22 in which are engaged the outer ends of a pair 60 of guy-rods 23, the same diverging outwardly and upwardly to engage with hooks 24, secured in the wall 10 adjacent to the sides of the window frame at its extreme 65 upper end.

Resting upon the head 17 is a circular plate 25, having a raised hub portion 26 at its center containing an opening for the bar 18, and formed with the margin of the plate 70 25 is an annular raised element 27, its upper edge cut diagonally, forming a cam surface 28, opposed to which is a similar cam surface 29 on the downwardly extending flange 30, formed with another circular plate 31 75 having a raised hub 32, upon which the head 21 of the rectangular bar 18 normally rests.

An inwardly extending hub 33 is formed with the plate 31, the same having an opening suited to receive the bar 18, the hub 33 80 having a cylindrical exterior upon which is rotatably engaged a sleeve 34, resting upon ball bearings 35, engaged within the recess of the hub 26 so that it may freely rotate within the casing formed by the elements 85 25, 27, 30, and 31.

A cover plate 36 is secured by screws 37 to the upper flanged portion 38 of the sleeve 34 and engaged between arms extending 90 from the flange 38 and cover plate 36, on pins 39, are a plurality of arms 40, the same extending outward between the cam faces 28 and 29 and rotate with the hub 34. The arms 40 extend out to a considerable distance from the axis of the structure and are 95 provided with heads 41, having recesses 42 and 43 adapted to receive a wash line or cord 44.

Fixed upon the wall 10, at each side of and midway in the height of the window 100 are brackets 45, carrying rods 46 which have pivot pins 47 at their outer ends engaging rectangular blocks 48 so that the blocks may be rotated upon the end of the rods 46.

Engaged with the forked ends of the 105 blocks 48, on pins 49 are the hinged elements 50 of strips 51, normally extending toward the brackets 45 and provided with lugs 52, extending outwardly so as to make contact with the surface of the rods 46 when 110 the blocks 48 are in a horizontal position.

Plate arms 53 extend from the blocks 48

and rigidly inserted therein are spindles 54, having enlarged heads 55 at one end and provided with reduced screw-threaded ends 56 upon which are engaged nuts 57, the same 5 making contact with cups 58 carrying a plurality of balls 59 and constituting ball bearings in which the hubs 60 rest, the hubs rotating upon the spindles 54. Formed with the hubs 60 are a plurality of arms 61, terminating in flat heads 62 containing recesses 63, adapted to receive the cord 44.

Referring to Fig. 1, it will be seen that the line 44 passing closely in front of the window 11, is supported and guided by passing over the smaller wheels and engaging with the arms 40, which are raised and lowered due to their cam engagement as they are rotated. After the line 44 has been removed the latch elements 51 are turned outwardly, permitting the blocks 48 to assume a vertical position, as shown in the dotted line in Fig. 5, at that time hanging suspended beside the wall of the building.

In the modification shown in Figs. 6 and 25 7, the construction is the same so far as the cam actuated and smaller wheels, together with the support bracket, but the supporting connections between the smaller support wheels and the bracket are so constructed 20 that the smaller wheels, together with the cord, may be entered inwardly through the window opening so as to receive the laundry articles thereon preliminary to extending and drying.

35 In this adaptation the rods 46 are extended vertically upward, as at 65, and on them are pivoted laterally extending plate elements 66 carrying pivot pins 67, supporting arms 68, connected by a transverse bar 40 69, the arms 68 when extended resting on lugs 70, formed with the latch elements 71

pivoted upon pins 72 in the plates 66, the smaller wheels, generally denominated by the numeral 60, being pivoted upon pins set in the transverse bar 69 in a manner which 45 is clearly apparent in Fig. 6.

Thus the bar 69 may be turned inwardly through the window permitting the clothing to be secured in a convenient manner and without leaning outward from the window, preventing danger to the operator, who, by merely pulling the cord 44 in the desired direction, is enabled to pass the clothing outward through the opening or, in the preferred embodiment, causing the 55 cord to move in a circular path upon the outer drier arms. The device sliding freely upward upon the vertical rods 65, so that the clothing is not brought in contact with the window sill when moved out and when 60 the device is not in use the wheels 60 may hang suspended as shown in Fig. 7.

Having thus described my invention what I claim as new and desire to secure by Letters Patent, is—

In a wash hanger, the combination with a support extending diagonally upward from the wall of the building, a cam fixed upon said support, said cam having a diagonal groove in the peripheral face thereof, 70 a hub rotatably mounted interiorly of said cam, a plurality of arms radiating from said hub engageable in the groove of said cam whereby they are alternately raised and lowered as they are rotated, a pair of 75 spoked pulleys pivotally mounted adjacent to a window in said wall, recesses formed at the ends of said spokes and the ends of said arms adapted to receive a cord.

In testimony whereof I have affixed my 80 signature.

STANLEY WASZKIEWICZ.
